UNITED STATES PATENT OFFICE

138,812

DESIGN FOR A BIB OR SIMILAR ARTICLE

George D. Brown, West Los Angeles, Calif.

Application June 8, 1944, Serial No. 113,908

Term of patent 7 years

(Cl. D3—26)

To all whom it may concern:

Be it known that I, George D. Brown, a citizen of the United States, residing at West Los Angeles, in the county of Los Angeles and State of California, have invented a new, original, and ornamental Design for a Bib or Similar Article, of which the following is a specification, reference being had to the accompanying drawing, forming part thereof.

The figure is a plan view of a bib or similar article, showing my new design.

I claim:

The ornamental design for a bib or similar article, as shown.

GEORGE D. BROWN.
